Dec. 1194

Theodore W. Gillagore, of Philadelphia, Pa.
Designor, to Savery & Co. of same place.
Letters Patent No. 1194. Dated Jan 4, 1860.

The schedule referred to in these Letters Patent and making part of the same.

To all whom it may concern,

Be it known that I, Theodore W. Gillagore, of the City of Philadelphia, in the State of Pennsylvania, have invented or produced a new and original Ornamental Design for "fire-dogs", and I do hereby declare that the following is a full, clear and exact description of the same, reference being had to the annexed drawing, making a part of this specification, and to the letter of reference marked thereon.

The said design I call the "Angular" Pattern; and it consists of a representation of two, conjoined, ornamental, angular, open parts, supported upon an ornamented base - as hereinafter described - to be cast in metal and used as the front part of a "fire-dog".

The drawing A & B represent the two, angular, open parts, and, C, the ornamental base.

The edges d-d. of the angular parts, (A & B), are "half-rounded", producing the flat facing e-e; the four, outer angles being knobbed, f-f, and the upper end trilobate, as seen in the drawing. Over the place of junction of the two angular parts, A & B, there is also a trilobate ornament g.

The base, C, is bifurcate, as usual, and is ornamented, as shown in the drawing - the same connecting with the angular parts, A & B, by the intermedia - ting moulding h; and just below this moulding, are two scrolls i, i, surmounting a plain face, K, which is suitable for the name of the manufacturer.

The outer edges of the legs are ornamented with the lobes l, l, and m, m. The whole is of the configuration shown in the drawing.

What I claim as my invention and desire to secure by Letters Patent, is The herein described configuration and ornamentation, consisting of the two angular, open parts (A & B) and the base (C), as a new and original ornamental design for "fire-dogs". Ex'd.
